(57) **CLAIM**

The ornamental design for terminal holder for reduced crosstalk connector, as shown and described.

DESCRIPTION

FIG. 1 is a perspective view of a terminal holder for reduced crosstalk connector showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; the opposite side being a mirror image of that shown;

FIG. 7 is a perspective view thereof, in installed condition at 45 degrees;

FIG. 8 is a perspective view thereof, in installed condition at 90 degrees; and,

FIG. 9 is a perspective view thereof, in installed condition at 180 degrees.

The broken line showing of the environment is for illustrative purposes only and forms no part of the claimed design.
